UNITED STATES PATENT OFFICE

JACOB BERLINGER, OF BROOKLYN, NEW YORK

DESIGN FOR A FINGER RING OR SIMILAR ARTICLE

Application filed August 21, 1930. Serial No. 36,728. Term of patent 14 years.

To all whom it may concern:

Be it known that JACOB BERLINGER, a citizen of the United States, and resident of Brooklyn, in the county of Kings and State of New York, has invented a new, original, and ornamental Design for Finger Ring or Similar Article, of which the following is a specification, reference being had to the accompanying drawing, forming part thereof, in which,

Fig. 1 is a perspective view of a finger ring embodying my new design; and
Fig. 2 is a side edge view thereof.

I claim:

The ornamental design for a finger ring or similar article, substantially as shown.

Dated, New York, August 20, 1930.

JACOB BERLINGER.
